DESIGN FOR A SET OF BOOK ENDS

Lewis P. Weil, Cynwyd, Pa.

Application March 28, 1942, Serial No. 106,357

Term of patent 7 years

To all whom it may concern:

Be it known that I, Lewis P. Weil, a citizen of the United States, residing in Cynwyd, in the county of Montgomery, State of Pennsylvania, have invented a new, original, and ornamental Design for a Set of Book Ends, of which the following is a specification, reference being had to the accompanying drawing, forming part thereof.

Fig. 1 is a side elevational view of a set of book ends, showing my design; and

Fig. 2 is a front elevational view thereof.

I claim:

The ornamental design for a set of book ends, as shown.

LEWIS P. WEIL.
